COUNTER FREQUENCY DIVIDER WITHOUT
TIME DELAYHarold Lifschutz, Washington, D. C., now by judi-
cial change of name Harold Lyons

Application April 6, 1942, Serial No. 437,813

4 Claims. (Cl. 250—27)

(Granted under the act of March 3, 1883, as
amended April 30, 1928; 370 O. G. 757)

1

This invention relates to electronic frequency dividers and more particularly to frequency dividers employing electronic counter circuits of the scale-of-two type.

It is well known in the art that electronic frequency dividers must, if the same are capable of practical utilization, operate in such a manner as to produce an output frequency of some sub-multiple of the input frequency and in synchronism therewith. It has been found advantageous in certain instances to utilize electronic counter circuits, of the scale-of-two type for example, as the primary components of electronic frequency dividers. However, due to certain inherent operating characteristics of conventional electronic counter circuits, the prior frequency dividers employing such circuits do not operate in the manner noted above. Electronic counter circuits of the scale-of-two type operate to generate one output pulse, of a certain polarity, upon application of every two input pulses of like polarity thereto. The output pulse is not generated at the instant the second pulse is applied to the circuit thus producing a time delay which is inherent in counter circuits of this type. Before electronic counter circuits may be employed to produce an efficient electronic frequency divider such time delay must be negated.

It is therefore an object of the present invention to provide an efficient electronic frequency divider that employs electronic counter circuits.

Another object is to provide means compensating for the time delay inherent in operation of conventional electronic counter circuits of the scale-of-two type whereby the latter may be employed in electronic frequency dividers.

Another object is to provide a frequency divider comprising a plurality of electronic counter circuits which operates to produce an output frequency of some sub-multiple of the input frequency and in synchronism therewith.

Another object is to provide a frequency divider that operates in response to equally spaced input pulses to produce equally spaced output pulses, in synchronism with the input pulses, at a frequency less than the frequency of the input pulses.

Still another object of the invention is to provide an electronic frequency divider having a scale-of-two counter circuit for producing an electrical impulse at the instant an electrical pulse is applied thereto, and being of such construction to render the circuit non-responsive to subsequent impulses applied thereto, with means responsive to a predetermined number of impulses to again render the counter circuit respon-

sive to application of an electrical impulse to produce a second impulse.

Still another object is to provide a frequency divider of the above type having a plurality of scale-of-two electronic counter circuits connected in cascade relation for producing an electrical impulse following application of a predetermined number of electrical impulses thereto for rendering a separate scale-of-two counter circuit responsive to an electrical impulse.

Other objects and features of the invention will appear more fully from the following detailed description when considered in connection with the accompanying drawing which discloses one embodiment of the invention. It is to be expressly understood, however, that the drawing is designed for purposes of illustration only and not as a definition of the limits of the invention, reference for the latter purpose being had to the appended claims.

In the drawing, wherein similar reference characters denote similar parts throughout the several views:

Fig. 1 is a schematic showing of an electronic counter circuit of the scale-of-two type employed by the present invention, and

Fig. 2 is a diagrammatic showing of an electronic frequency divider embodying the principles of the present invention.

With reference more particularly to Fig. 1 of the drawing, a conventional electronic counter circuit is disclosed therein which includes a pair of vacuum tubes 10 and 11 each including a cathode 12, 13 and a plate 14, 15 respectively. Plates 14 and 15 are respectively supplied with positive potential from point 16 through resistances 17 and 18, while cathodes 12 and 13 are connected together at point 19. Each of the tubes further respectively include a first control grid 20, 21, a second control grid or screen grid 22, 23 and a third control grid 24, 25. Control grids 20 and 21 are connected through resistance 26 to point 19; screen grids 22 and 23 are supplied with high positive potential as indicated on the drawing; while control grids 24 and 25 are connected through resistances 27 and 28, respectively, to a source of negative potential at point 29. Electrical impulses to be counted are supplied to the circuit through input terminal 30, which is connected to control grids 20 and 21, while the output of the circuit is fed through capacitance 31 to terminal 32. The output of tube 10 is connected to the input of tube 11 by a connection from plate 14, through resistance 33, to grid 25, while the output of tube 11 is connected to the input of tube 10 by means

of a connection, including resistance 34, between control grid 24 and plate 15. The foregoing connections form a two-stage resistance coupled amplifier with regenerative feedback in which resistances 33 and 34 are respectively bypassed by capacitances 35 and 36, of small capacity, in order to obtain strong coupling and positive action of the circuit.

The foregoing circuit possesses two states of equilibrium, namely, first, when tube 10 is in a conducting state while tube 11 is not in a conducting state, and second, when tube 10 is not conducting while tube 11 is conducting. Whenever a negative electrical impulse is applied to grids 20 and 21, through input terminal 30, the tube in the conducting state is rendered less conducting, while the tube that was not passing the current is rendered conducting after the negative impulse to either grid 20 or 21 diminishes, consequently blocking the tube that was originally conducting. This action produces a positive or a negative impulse at the output of each of the tubes, the tube that is rendered conducting producing a negative pulse, while the tube that is blocked produces a positive impulse. This action continues upon application of each negative impulse to the circuit, and each of the tubes therefore alternately produce negative impulses upon application of alternate negative impulses to input terminal 30. Since output terminal 32 is connected to plate 15 it can be readily seen that one negative impulse is applied thereto for each two negative impulses applied to the circuit.

As mentioned heretofore, conventional electronic counter circuits of the scale-of-two type, such as an electronic counter circuit of the type discussed heretofore, possess an inherent time delay which renders similar circuits incapable of operating as efficient frequency dividers. Assuming an application of a negative impulse to grids 20 and 21, when tube 10 is passing current while tube 11 is in a non-conducting state, a positive pulse appears at the output of tube 10 when the tube is cut off. However, the negative impulse of the tube 11 will not appear at the same instant since the tube will not be rendered conducting until such negative potential diminishes from the grid thereof. It can be readily seen, therefore, that the negative pulse at terminal 32 does not appear at the instant the second negative impulse is applied to input terminal 30, and for this reason electronic counter circuits are not capable to operate as efficient electronic frequency dividers without providing means compensating for such time delay.

In Fig. 2 of the drawings, an electronic frequency divider constructed in accordance with the principles of the present invention is disclosed therein including an electronic counter circuit of the scale-of-two type indicated generally at A. This counter circuit is similar to the counter circuit previously described with the exception that the impulses applied thereto, through input terminals 30, are only applied to grid 20. In this embodiment cathodes 12 and 13 are connected together; however, grids 20 and 21 are connected to their respective cathodes through resistances 37 and 38. Also, in this embodiment, the output terminal 39 is connected through capacitance 40 to plate 14 of tube 10. Since the negative impulses from input terminal 30 are only applied to grid 20, the circuit will

only be affected thereby when in that state of equilibrium in which tube 10 is passing current and tube 11 is in a non-conducting state. With the circuit in the foregoing condition, the negative impulse applied to grid 20 cuts off the plate current flow in tube 10 causing a positive pulse to appear at output terminal 39 at substantially the instant a negative impulse is applied to grid 20, while also rendering tube 11 in a conducting state. Since tube 10 is maintained in a non-conducting state by a negative potential on grid 24, and since the negative impulses from input terminal 30 are not applied to grid 21 of tube 11, application of subsequent negative pulses from input terminal 30 will not affect the counter circuit.

In accordance with the principles of the present invention, means are provided for rendering the counter circuit responsive to a negative impulse, from terminal 30, after a predetermined number of negative impulses are applied thereto following the initial negative impulse, to produce another positive impulse at output terminal 39 at substantially the instant a certain negative impulse is applied to the counter circuit. As shown in Fig. 2, such means includes a plurality of electronic counter circuits 41, 42, 43 and 44, which respectively comprise the first, second, third and nth stages of a counter arrangement. Each of the stages comprise an electronic counter circuit of the scale-of-two type, such as the type disclosed in Fig. 1, connected in cascade as distinguished from a ring connection. The term cascade connection indicates that type of connection of a plurality of scale-of-two counter circuits in which only the first circuit of the group is connected to receive the incident pulses to be counted, subsequent circuits of the group each receiving triggering impulses from the next preceding circuit only. Since, as stated heretofore, the scale-of-two counter circuit disclosed in Fig. 1 produces one negative impulse at output terminal 32 for each two negative impulses applied thereto from terminal 31, it can be readily seen that the counter arrangement disclosed in Fig. 2 produces one negative impulse upon application of a predetermined number of negative impulses thereto. For example, with a counter arrangement comprising stages 41, 42, 43 and 44 connected in cascade relation, the number N of negative impulses applied to the first stage through input conductor 45 for producing a negative impulse at output conductor 46, of stage 44, is equal to 2 raised to a power equal to the number of stages connected in cascade relation. When considering 4 stages connected in cascade relation, 16 negative pulses must be applied to the first stage, through terminal 45, before a negative impulse appears at terminal 46. It is to be expressly understood that any number of scale-of-two electronic counters or stages may be connected in cascade relation to obtain an output pulse at terminal 46, after application of any predetermined number of negative impulses to the first stage. The foregoing counter arrangement is connected to the electronic counter circuit, designated generally at A, in such a manner to render tube 10 responsive to a negative impulse after an impulse is produced at terminal 46. Input terminal 30 is connected to input terminal 45 so that negative impulses are applied to stage 41 and to grid 20 simultaneously,

while the output of stage 44 is connected, by way of terminal 46, to grid 21 of tube 11.

On operation of the frequency divider described heretofore, assuming tube 10 to be passing current while tube 11 is in a non-conducting state, upon application of a negative impulse to input terminal 45, grid 20 is driven sufficiently negative to block tube 10 to thus cause a positive impulse to appear at output terminal 39 at substantially the instant the negative pulse is applied to grid 20, while at the same time, actuating stage 41 of the plurality of counter circuits connected in cascade relation. Upon the application of the next negative impulse, tube 10 will not be affected for the reasons mentioned heretofore, while the counter circuit comprising stage 41 produces an output pulse which initiates actuation of stage 42. After a number of negative impulses, equal to 2 raised to a power equal to the number of stages connected in cascade relation, are applied to the first stage from terminal 45, a negative readying impulse appears at terminal 46 and produces a negative bias on grid 21 of tube 11. Tube 11 is thus rendered non-conducting and, due to the regenerative action of the counter circuit, tube 10 is rendered conducting or placed in such a condition that the tube is responsive to the next negative impulse applied to grid 20. Upon application of the next negative impulse from the terminal 45, tube 10 is cut off thus generating another positive impulse at terminal 39 and again rendering tube 10 non-responsive to subsequent negative impulses. It is to be expressly understood, therefore, that the impulse at terminal 39 appears simultaneously when the first negative impulse is applied to terminal 45, and thereafter impulses appear at terminal 39 simultaneously upon application of every Nth negative impulse applied to terminal 45, where N equals 2 raised to a power equal to the number of scale-of-two counter circuits connected in cascade relation. With this arrangement an efficient frequency divider is provided which functions to produce impulses at the instant certain negative impulses are applied thereto. Since the scale-of-two counter A is actuated directly by the impulses applied from terminal 45 no time delay is present between the input and the output of the frequency divider, the positive output impulses being generated at substantially the instant negative impulses are applied to grid 20, with tube 10 in a conducting state. Counter circuits 41, 42, 43 and 44 function to determine the frequency reduction of the output impulses of scale-of-two counter A, and it is to be expressly understood that substantially any number of scale-of-two counter circuits may be connected in cascade relation to provide varied frequency reductions.

Since counter circuits 41, 42, 43 and 44 function to determine the frequency reduction of the output of counter circuit A, these circuits must operate to produce a negative impulse to render tube 10 conducting, when the Nth negative impulse is applied to terminal 46, before the input negative impulse following the Nth pulse is applied from the input terminal. The maximum input frequency that may be employed then depends upon the number, and the speed of operation, of the scale-of-two counter circuits connected in cascade relation. In order to provide a circuit which allows operation of the highest maximum frequency, high speed counter circuits are provided in each of the stages, and the stages are interconnected in such a manner as to nullify

the time delay between each stage. With reference to Fig. 1 of the drawing, an arrangement is disclosed therein for interconnecting the counter circuits in cascade relation to allow operation thereof without a time delay. As shown, a vacuum tube 47 is provided which includes a plate 48, cathode 49 and a control grid 50. Plate 48 is maintained at high positive potential by a connection through resistance 51 to point 16, while cathode 49 is connected to cathodes 12 and 13. Output terminal 32 is connected to control grid 50, while the latter is maintained at negative potential by a connection through resistance 52 to point 53. Output terminal 54, which supplies negative impulses to the next stage, is connected to plate 48 through capacitance 55. Since control grid 50 is maintained at negative potential tube 47 will not be effected upon the application of negative impulses from terminal 32; however, when positive pulses are generated in the output of tube 11 control grid 50 is driven positive to allow tube 47 to pass current and thus generate a negative impulse at output terminal 54. Since positive impulses are generated at the output of tube 11 at substantially the instant negative impulses from terminal 30 are applied to grids 20 and 21 it can be readily seen that tube 47 will pass current and generate a negative impulse at terminal 54 at substantially the same instant.

There is thus provided by the present invention an electronic frequency divider, employing electronic counter circuits of the scale-of-two type, which operates to produce an output at a frequency less than the input frequency and in synchronism with the latter. The arrangement disclosed herein is of such design to compensate for certain time delays inherent in operation of conventional electronic counter circuits and is thus capable to produce equally spaced impulses, in synchronism with and at any desired frequency less than the frequency of equally spaced input impulses. Moreover, the present invention provides means for connecting a plurality of electronic counter circuits of the scale-of-two type in cascade relation to allow operation without a substantial time delay.

Although several embodiments of the invention have been disclosed and described herein, it is to be expressly understood that various substitutions and changes may be made therein without departing from the spirit of the invention as well understood by those skilled in the art. For example, any scale-of-two type of counter circuit may be employed in the manner disclosed and described heretofore, such as triode or triple grid counter circuits. Reference therefor will be had to the appended claims as a definition of the limits of the invention.

The invention described herein may be manufactured and used by or for the Government of the United States of America for governmental purposes without the payment of any royalties thereon or therefor.

What is claimed is:

1. A frequency divider comprising a plurality of electronic counter circuits of the scale-of-two type connected in cascade relation, a separate electronic counter circuit of the scale-of-two type ineffective to influence the cascade, means simultaneously applying incident electrical impulses to only the first circuit of said cascade and to said separate circuit, an output circuit individual to said separate circuit, means in said separate circuit for generating an electrical impulse in 75 said output circuit at the instant the first inci-

dent impulse is applied, other means in said separate circuit for rendering the latter non-responsive to application of electrical impulses following said first impulse, and means responsive to the output of said cascade for rendering said separate circuit responsive to the application of the next impulse following a predetermined number of impulses subsequent to said first impulse.

2. An electronic frequency divider comprising a plurality of scale-of-two counter circuits, means connecting n number of said circuits in cascade relation for producing an electrical impulse at the last circuit of said cascade upon application of 2^n number of electrical impulses to the first stage thereof, means simultaneously applying electrical impulses to said first circuit and to a separate circuit of said plurality, said separate circuit responsive to application of the first electrical impulse for producing an electrical impulse, means in said separate circuit for rendering the latter non-responsive to application of electrical impulses following said first impulse, and means responsive to the output of said cascade for rendering said separate circuit responsive to application of another electrical impulse whereby said separate circuit produces a second impulse upon application of the 2^n+1 impulse thereto.

3. A frequency divider comprising a plurality of scale-to-two counter circuits, each of said circuits including a pair of multiple grid vacuum tubes, certain of said circuits interconnected in such a manner whereby each of said tubes alternately produce positive and negative impulses upon application of negative impulses thereto, said positive impulses appearing substantially at the instant of application of alternate negative impulses, means connecting said certain circuits in cascade relation, the last-named means including means responsive to positive impulses generated by one circuit for generating a negative impulse that is applied to the input of the next circuit of said cascade, another of said scale-of-two counter circuits having said pair of vacuum tubes interconnected in such a manner as to render either of said tubes non-conducting to produce a positive impulse and the other tube conducting upon application of a negative impulse to a grid of the tube rendered non-conducting, means applying negative impulses to the grid of 50

one of said tubes of said another circuit whereby the latter tube is rendered non-conducting while the other tube of said another circuit is rendered conducting upon application of the first negative impulse when said one tube is conducting, means 5 simultaneously applying said negative impulses to the first circuit of said cascade whereby a negative impulse is produced at the last circuit of said cascade upon application of a predetermined number of said negative impulses thereto, and means applying the output of said cascade to a grid of the other tube of said another circuit for rendering said one tube conducting and responsive to application of the negative impulse following said predetermined number of negative impulses.

4. A frequency divider comprising a plurality of electronic counter circuits each having an input and an output terminal, means connecting all of said circuits in cascade relation, and an additional counter circuit of the scale-of-two type having a separate input terminal for each of two cross-connected electron discharge devices, one of said separate input terminals being connected only to the output terminal of the last circuit of the cascade, and means simultaneously applying electrical impulses to the input terminal of only the first circuit of said cascade and the other of said separate input terminals of said additional counter circuit.
